(57) CLAIM

I claim the ornamental design for a crossbow, as shown and described.

DESCRIPTION

FIG. 1 is a perspective, side view thereof;
FIG. 2 is a right side view thereof; and,
FIG. 3 is a left side view thereof.

The broken lines in FIGS. 1-3 are for illustrative purposes and form no part of the claimed design.

1 Claim, 2 Drawing Sheets

FIG. 3
